BRUSH

Albert R. Racicot, Aurora, Ill., assignor to National Brush Company, Aurora, Ill., a corporation of Illinois

Application August 5, 1953, Serial No. 26,294

Term of patent 14 years

(Cl. D9—2)

To all whom it may concern:

Be it known that I, Albert R. Racicot, a citizen of the United States, residing at 419 Oak Avenue, Aurora, State of Illinois, have invented a new, original, and ornamental Design for a Brush, of which the following is a specification, reference being had to the accompanying drawing, forming a part thereof in which:

I claim:

The ornamental design for a brush, substantially as shown.

ALBERT R. RACICOT.
